FIG. 6.

UNITED STATES PATENT OFFICE.

FREDERICK J. NASH, OF SOMERVILLE, MASSACHUSETTS, ASSIGNOR TO UNITED SHOE MACHINERY COMPANY, OF PATERSON, NEW JERSEY, A CORPORATION OF NEW JERSEY.

LEATHER-SPLITTING MACHINE.

No. 894,850.

Specification of Letters Patent.

Patented Aug. 4, 1908.

Application filed May 6, 1904. Serial No. 206,732.

To all whom it may concern:

Be it known that I, FREDERICK J. NASH, a citizen of the United States, residing at Somerville, in the county of Middlesex and 5 Commonwealth of Massachusetts, have invented certain Improvements in Leather-Splitting Machines, of which the following description, in connection with the accompanying drawings, is a specification, like 10 reference characters on the drawings indicating like parts in the several figures.

This invention relates to machines for splitting and evening leather and has for its object to provide an improved machine for 15 this purpose.

The machine herein shown as embodying the invention is particularly adapted for operating on soles and other small pieces of leather, but it is to be understood that many 20 features of the invention are applicable also to machines adapted for splitting large pieces of leather, such as whole sides.

The present machine is designed especially for evening soles,—that is, reducing a 25 number of soles to the same thickness. It is customary to sort soles into various grades according to approximate thickness computed in forty-eighths of an inch and to even the soles in each grade by splitting from the 30 flesh side of each sole enough stock to reduce it to the exact thickness of the grade into which it has been placed. The machine of the present invention is, therefore, provided with a splitting knife and a pair of feed rolls, 35 one of which rolls is held in rigid relation to the knife at a distance above the knife equal to the desired thickness of sole, while the other feed roll is yieldingly mounted to enable it to adapt its position to the thickness of 40 stock being fed. The rolls force the stock against the knife and the sole passes between the rigid roll and the knife while the surplus material split off from the sole passes between the yielding roll and the knife. The 45 rigid feed roll is adjustable to adapt the machine for evening different grades of soles, and means is provided, herein shown as a pointer movable over a graduated plate, for indicating to the operator the degree of adjustment of the roll for each grade of sole.

It is desirable to mark the soles to indicate their grade and the machine of the present invention is preferably provided with stamping mechanism for this purpose. The 55 stamping mechanism shown as embodying

one form of my invention comprises a reciprocating member and a normally stationary coöperating member. One of said members supports a plurality of dies, any one of which may be brought into position for stamping the desired mark to indicate the grade or thickness of soles being evened. As herein shown, the dies are carried by the normally stationary member, which, to this end, is made in the form of a rotatable block with 60 dies secured in or upon its periphery. Preferably the die-carrying member or die carrier, as it may be called, is arranged to be adjusted for putting the proper die into operative position by means which is operated 65 simultaneously with the means for adjusting the rigid feed roll. By this arrangement the stamping mechanism is always adjusted so that it will mark the sole in accordance with the grade for which the evening mechanism is adjusted.

As I am advised, I am the first to provide a machine comprising mechanism for splitting or evening stock and mechanism for marking the thickness of the stock produced, 80 in combination with means independent of the stock being fed for simultaneously adjusting the splitting and marking mechanisms, and this is one important feature of my invention.

Preferably the die carrier will be so constructed and arranged that when it is adjusted for marking thin stock its acting face will be brought closer to the reciprocating member than when it is adjusted for marking 90 thick stock, in order that the stamping mechanism may act uniformly on stock of different thicknesses.

These and other features of the invention, including certain details of construction and 95 combinations of parts, will be set forth in detail in the following description and pointed out in the claims.

Figure 1 is a front elevation of the machine. Fig. 2 is a left-hand view, the driving pulleys being removed and certain other portions broken away. Fig. 3 is a partial longitudinal section. Fig. 4 is a vertical transverse section. Fig. 5 is a plan view of the knife and its adjusting screws. Fig. 6 is a 105 front elevation of the stamping die, the face plate being removed.

The frame 1 is constructed to rest upon a bench and is provided with bearings to support a driving shaft 2 on which are mounted 110

fast and loose pulleys 4 and 6. The driving shaft is provided with pinions 10 and 12 for driving the feed rolls 14 and 16. The pinion 10 meshes with an intermediate gear 18, 5 which in turn drives a large gear 20 fixed to the shaft 22 of the upper feed roll, as shown in Fig. 2. The pinion 12 meshes directly with a large gear 24, which is fixed on the shaft 26 of the lower feed roll, as shown in Fig. 4. By 10 this means both the feed rolls 14 and 16 are driven positively so that the work is fed with certainty.

The machine frame has at either end up-standing posts 25 which are forked, and the 15 shaft 26, carrying the lower feed roll 16, extends between the forks of these posts 25 and has bearing in arms or hangers 30. The hangers are pivotally connected by pins 32 to lugs 34 projecting rearwardly from the bearings 20 which support the driving shaft 2, all as shown in Fig. 2. The forward portions of the hangers 30 rest on strong springs 38 which serve to sustain the lower feed roll in a yielding manner. The lower ends of the 25 springs 38 rest on disks 40 sustained on screw bolts 42 having bearings in lugs 44 of the machine frame. By adjusting the bolts 42 the tension of the springs 38 may be varied, and thereby the force with which the yielding feed 30 roll is upheld may be increased or diminished. The normal elevation of the yielding lower feed roll is determined by stop-screws 50 which have bearing in lugs 52 of the frame and are adapted to contact with the forward 35 ends of the hangers 30.

The upper feed roll has bearing in blocks 60 which fit into the forks of the posts 25. The blocks are channeled at their front and rear faces, as indicated by dotted lines in 40 Fig. 4, so as to embrace the forks of the posts and be guided by them. The forks of the post are recessed, as at 62 (see Fig. 2), to provide seats for springs 64 upon which rest lugs 66 formed on the front and rear sides of the bearing blocks 60, whereby the blocks, and therefore the upper feed roll, are yieldingly 45 pressed upward.

The position of the upper feed roll is adjustably determined by stops 70 in the shape 50 of wedges formed on the lower face of a bar 72, as shown most clearly in Fig. 3. The stops engage similarly shaped lugs 74 formed on the upper faces of the bearing blocks 60. The bar 72 is arranged to be moved longitudinally between the bearing blocks 60 and a steel cap plate 78 which spans the space between the posts 25 and is firmly bolted to said posts. The bar is moved by means of a screw bolt 76 mounted to rotate without 55 longitudinal movement in a flange of the cap piece 78, said screw bolt having threaded engagement with a lug 80 on the bar. By turning the screw bolt in one direction or the other the bar may be moved to the left or to 60 the right for forcing the bearing blocks 60 and

the upper feed roll 14 down or permitting said parts to be raised by the springs 64. A hand wheel 82 is secured to the screw bolt 76 for conveniently operating the sliding bar. The sliding bar may be adjusted vertically 70 for the purpose of positioning the upper feed roll by means of a set screw 88 mounted in the cap piece 78 and bearing on a plate 89 which rests upon the left-hand end of the sliding bar. By turning the set screw in one 75 direction or the other the left-hand end of the sliding bar may be depressed or permitted to rise, under influence of the supporting springs 64, for putting the upper feed roll into parallel or other desired relation to the cutting 80 edge of the splitting knife to be described.

The splitting knife 90 is supported on a shelf 92 preferably formed integral with the machine frame, as shown in Fig. 4. The knife is provided in its rear edge with 85 threaded holes to receive screw bolts 94 and the shelf is provided with upturned ears 96 which are forked to receive an unthreaded portion of the bolts 94 and to fit between the flanges on the bolts so as to hold the bolts 90 against longitudinal movement while permitting them to be turned for adjusting the knife toward and from the feed rolls. The knife is secured in position after having been adjusted by a plate 97 and bolts 98, the heads 95 of the bolts being countersunk in the plate 97. The bolts pass through elongated slots 99 in the knife and through openings in the shelf 92, and are held in place by suitable nuts applied to their lower ends. The arrangement of the adjusting bolts 94 in the forked ears 96 is such that the plate 97 having been first taken off, the knife may be removed from the machine without disturbing the position of the adjusting bolts 94 in the 100 knife, and the knife may therefore be replaced in exactly its former position. This construction has the advantage that it obviates the necessity for entirely readjusting the knife each time it is replaced in the machine. 110

It will be understood from the above description that the knife occupies a fixed position, that the upper feed roll is adjustable up and down from and toward the plane in which the knife is located to vary the thickness of the stock and that the lower feed roll is so supported that it may yield downwardly to accommodate irregularities or variations in the thickness of the stock. This arrangement will insure that the finished articles, 115 such as soles, passing through the machine between the upper feed roll 14 and the knife will always be reduced to an even and uniform thickness with a given adjustment of the upper feed roll. The normal position of 120 the lower feed roll 16 may be adjusted by means of the stop-screws 50 to provide for varying the amount of material removed from the lower side of the stock. By properly adjusting the two feed rolls with relation 125 130

to the knife the machine may be employed to split leather articles into two pieces of the same or different thicknesses, as desired. The knife may be adjusted by the screw bolts 94 toward and from the vertical plane passing centrally through the feed rolls, it being advantageous to have the edge of the knife nearer to this plane when splitting thin stock than when splitting thick stock, as is well understood by those familiar with this art.

For the purpose of indicating the thickness of work which will pass between the upper feed roll and the knife in any given adjustment of the upper feed roll, a pointer 100 is pivotally connected at 103 to the cap piece 78 and has its lower end forked to engage a block 102 pivoted on the slide bar 72. The upper end of the pointer is guided over a plate 104 which is marked to indicate the different thicknesses of soles usual in the trade.

The machine is equipped with mechanism for stamping articles to be operated upon with a figure or other mark indicating the thickness of the finished sole or other article which the machine is adjusted to produce. This mechanism comprises an eccentric 110 mounted on the driving shaft 2 and surrounded by an eccentric strap 112 having connection with the rear end of a lever 114. The lever is pivoted at 116 to the machine frame and its front end is jointed to a plunger 118. The plunger receives over its upper end the sleeve of a block 120, which is sustained yieldingly on the plunger by means of a spring 122. The lower portion of the sleeve is provided with slots to receive the ends of a pin 124 in the plunger which prevents the block from turning on the plunger and also limits the movement of the block longitudinally of the plunger. Co-operating with the plunger 118 and block 120 is an adjustable block 130, which serves as an anvil and in the present machine is the die-carrying member of the stamping mechanism. Preferably, and as herein shown, this member is a rotatable block mounted on a fixed stud or pin and into the periphery of which are set a series of dies 132 having characters embossed thereon for stamping the desired marks on the stock. For the purpose of adapting the stamping mechanism to operate uniformly upon pieces of stock differing in thickness the die-carrying block has an eccentric periphery, the dies being arranged at different distances from the point of support of the block, those dies intended for stamping the thickest stock being located at points nearest the point of support of the block and those dies intended for stamping thinner pieces of stock being located at greater distances from said point of support.

Connections are provided between the

sliding bar 72, by which the position of the upper feed roll is adjusted, and the die-carrying block 130, so that the feed roll and block shall be simultaneously adjusted to insure that the stamping mechanism shall mark on the stock a thickness character corresponding to the thickness of stock for which the feed roll is adjusted. To this end the slide bar 72 has projecting forwardly from it a lug 140 which receives a screw 142 having adjustable connection with a rack bar 144. The rack bar 144 engages a pinion formed on a shaft 146, which also carries a pinion 148 adapted to mesh with a pinion 150 fast on the hub 152 of the die-carrying block, see Figs. 1 and 2. By means of these connections the die-carrying block is rotated to adjust it simultaneously with the adjustment of the upper feed roll. The adjustable connection between the rack bar 144 and the lug on the sliding bar 72 permits the relation of the die-carrying block and the upper feed roll to be accurately determined in setting up the machine and also permits an independent adjustment of these parts, if that should be desired. The die-carrying block has in its front face an annular chamber which receives a spiral spring 158. One end of the spring is secured at 160 to the hub of the block, while the other end of the spring is provided with a hook 164 which is adapted to engage with a pin 166 carried by a removable face plate 168 adapted to fit over the front of the die-carrying block and to be rigidly secured by means of a nut 170 to the stud on which the die-carrying block is mounted. The face plate may be adjusted axially about the stud to cause the pin 166 to hold the spring 158 under desired tension. The spring serves the function of holding the block yieldingly turned in a contra-clockwise direction as far as the position of the rack bar 144 will permit, and thus prevents any back-lash of the die-carrying block in case the rack bar or pinions do not fit snugly.

The machine is provided in front of the feed rolls with a table 172 which is adapted to support the stock as it is fed into the machine, and the table has a rod 174 arranged to act as a guide for the work as it is presented to the feed rolls. The table is pivotally connected to the machine frame at 176 and may be turned into the dotted line position shown in Fig. 4 for allowing ready access to the feed rolls.

Preferably, and as herein shown, the pinions 10 and 12 and gears 18, 20, and 24 are provided with double-inclined or herring-bone teeth. This secures a powerful feed of the work by the feed rolls 14 and 16 with a steady and even progression, as distinguished from the step-by-step feed produced when the feed rolls are driven by gears having straight teeth, especially after the gear teeth have become somewhat worn and con-

sequently fit loosely together. The gears having inclined teeth also have the advantage that they are noiseless.

In using the machine the upper feed roll and the die-carrying member of the stamping mechanism are adjusted for the grade of soles to be evened or for the thickness of stock, of whatever kind, which is to be turned out. The stock is presented first to the stamping mechanism which impresses upon its upper surface or grain side the character indicating the thickness for which the feed rolls and knife have been adjusted, and then the stock is presented to the feed rolls which force it against the knife and split from the lower or flesh side enough material to reduce the sole or other article to the required thickness, the sole passing out of the machine between the knife and the upper feed roll, while the portion split off passes below the knife. The stamping mechanism is conveniently located at the left end of the machine so that the workman may with practically one movement present the stock to the stamping mechanism and then to the feed rolls.

By the expression "thickness of the stock" as used in the specification and particularly in the claims it will be understood that I mean the thickness of the sole or other article after it has been operated upon by the machine.

Having set forth the nature and objects of my invention and having specifically described a machine embodying the various features thereof in a preferred form, I claim as new and desire to secure by Letters Patent of the United States:—

1. In a machine of the class described, the combination with splitting means and an adjustable feed mechanism under control of the operator for presenting varying thicknesses of stock thereto, of marking mechanism operatively connected with the feed mechanism to be set according to the adjustment of the latter, and means for automatically actuating the marking mechanism to stamp the stock in accordance with the adjustment used.

2. In a machine of the class described, the combination with splitting means and an adjustable feed mechanism under control of the operator for presenting varying thicknesses of stock thereto, of automatically operated mechanism for marking the stock in accordance with the adjustment used.

3. In a machine of the class described, the combination with splitting means and an adjustable feed mechanism under control of the operator for presenting varying thicknesses of stock thereto, of mechanism controlled by the adjustment of the feed mechanism for marking the stock in accordance with the adjustment used.

4. In a machine of the class described, the

combination with splitting means, a feed mechanism for presenting the stock thereto, and means for adjusting the feed mechanism for varying the thickness of the stock, of a marking mechanism comprising a die-carrying member connected to be rotated by the movement of said adjusting means to cause the stock to be properly marked in accordance with the adjustment used, and a reciprocating member for said die.

5. In a machine of the class described, the combination with splitting means, a feed mechanism for presenting the stock thereto, and means for adjusting the feed mechanism for varying the thickness of the stock, of a marking mechanism comprising a die-carrying member connected to be rotated by the movement of said adjusting means to cause the stock to be properly marked in accordance with the adjustment used, means tending to turn said member oppositely to the force applied from the adjusting means, and a coöperating member for said die.

6. In a machine of the class described, the combination with a splitting knife, feed rolls for presenting the stock to the action of the knife, and means under control of the operator for adjusting the feed rolls and the knife relatively for varying the thickness of the stock, of automatically operated mechanism for marking the stock in accordance with the adjustment of the rolls and knife.

7. In a machine of the class described, a splitting knife, feed rolls for presenting the stock to the knife, and marking mechanism, in combination with means independent of the stock being fed for adjusting the feed rolls and knife relatively for varying the thickness of the stock produced and simultaneously adjusting the marking mechanism to cause it to mark the stock in accordance with the adjustment of the rolls and knife.

8. In a machine of the class described, a splitting knife, feed rolls for presenting the stock to the knife, and means, comprising a slide bar having cam faces, for adjusting one of the rolls relatively to the knife for varying the thickness of the stock, combined with marking mechanism comprising a die-carrying member, a coöperating member, and connections between said slide bar and said die-carrying member whereby when the feed roll is adjusted for varying the thickness of the stock said die-carrying member will also be adjusted to cause the stock to be properly marked.

9. In a machine of the class described, the combination with a splitting knife, feed rolls for presenting the stock to the action of the knife, and means under control of the operator for adjusting the feed rolls and knife relatively to vary the thickness of the stock, of mechanism for marking the stock controlled by the relative positions of said rolls and knife.

10. In a machine of the class described, a splitting knife, feed rolls for presenting the stock to the action of the knife, mechanism for marking the stock, means independent of 5 the stock being fed for adjusting the relative positions of the knife and rolls for varying the thickness of the stock to be split and also adjusting said mechanism to mark properly the thickness of the stock, combined with 10 means for indicating the thickness of stock for which the machine is adjusted.

11. In a machine of the class described, the combination with a splitting knife, feed rolls for presenting the stock to the action of the 15 knife, and mechanism for marking the stock, of a manually controlled adjusting device and operative connections between said device and one of the feed rolls and between said device and said marking mechanism for 20 positioning said feed roll relatively to the knife and adapting the marking mechanism to mark the work with a character indicating the thickness of stock for which the roll and knife are adjusted.

25. 12. In a machine of the class described, a splitting knife, feed rolls for presenting the stock to the knife, means for adjusting one of the feed rolls with relation to the knife for varying the thickness of the stock, and mechanism 30 for marking the stock, said mechanism comprising a rigidly supported member and a reciprocating member, and means for adjusting said rigidly supported member with relation to the reciprocating member to 35 compensate for the adjustment of the feed roll with relation to the knife whereby the mechanism is adapted to act uniformly upon the different thicknesses of stock produced.

13. In a machine of the class described, a 40 splitting knife, feed rolls for presenting the stock to the knife, and mechanism for marking the stock comprising a reciprocating member and a rigidly supported member, in combination with means for simultaneously 45 adjusting one of the feed rolls with relation to the knife and adjusting the rigidly supported member of the marking mechanism with relation to the reciprocating member.

14. In a machine of the class described, a 50 splitting knife, feed rolls for presenting the stock to the knife, and mechanism for marking the stock comprising a reciprocating member and an adjustable member carrying a plurality of dies, in combination with means 55 for simultaneously adjusting one of the feed rolls with relation to the knife and adjusting the die-carrying member to put the proper die into position to coöperate with the reciprocating member of the mechanism for marking 60 the stock in accordance with the adjustment of the feed roll and knife.

15. In a machine of the class described, a splitting knife, feed rolls for presenting the stock to the knife, and mechanism for marking 65 the stock comprising a reciprocating

member and a rotatable member carrying a plurality of dies, in combination with means for simultaneously adjusting one of the feed rolls with relation to the knife and rotating the die-carrying member to put the proper die into position to coöperate with the reciprocating member of the mechanism for marking the stock in accordance with the adjustment of the feed roll and knife, and yielding means tending to turn the die-carrying member in one direction and prevent backlash when said member is adjusted. 70

16. In a machine of the class described, a splitting mechanism comprising a splitting knife, feed rolls for presenting the stock to the knife, and a mechanism for marking the stock, in combination with means independent of the stock being fed for adjusting the feed rolls and the knife relatively for varying the thickness of stock and simultaneously 85 adjusting the marking mechanism to adapt it for marking properly the thickness of stock which the splitting mechanism is adjusted to produce whereby stock of varying thickness may be marked uniformly. 90

17. In a machine of the class described, a splitting mechanism comprising a knife and feed rolls for presenting the stock to the knife, and a marking mechanism comprising a reciprocating member and a coöperating member, one of which is provided with a plurality of marking dies, in combination with means for relatively adjusting the knife and one of the feed rolls for varying the thickness of the stock and simultaneously adjusting 100 the said marking dies to put the desired die into operative position to adapt the marking mechanism for properly marking stock of the thickness to be produced, and means for moving said reciprocating member with relation 105 to the coöperating member. 95

18. In a machine of the class described, a knife support, a knife provided with a screw-threaded aperture in its heel seated thereon, an upwardly-turned forked ear on said support adjacent to said aperture, a screw mounted for rotation without longitudinal movement in said ear and adapted to engage said aperture for adjusting said knife on its support, and means for securing said knife in adjusted position. 110

19. In a machine of the class described, a knife support, a knife provided with a screw-threaded aperture in its heel and an elongated opening in its body portion, seated 120 thereon, an upwardly-turned forked ear on said support adjacent to said aperture, a screw mounted for rotation without longitudinal movement in said ear and adapted to engage said aperture for adjusting said knife on its support, and a clamping bolt extending through said elongated opening and support for securing said knife in adjusted position. 125

20. In a machine of the class described, the combination with a rotatable die-carry- 130

ing block and means for adjusting the same, of a spiral spring having one end secured to said block and its other end secured to a fixed part, whereby said spring tends to turn the die-carrying block constantly in one direction and prevents loose movement relative to its adjusting means.

21. In a machine of the class described, splitting means, a feed mechanism for presenting stock thereto, means independent of the stock being fed for adjusting said mechanism to accommodate varying thicknesses

of stock, and a marking mechanism connected to be operated by said adjusting means to mark the stock in accordance with the thickness for which the feed mechanism is set. 15

In testimony whereof I have signed my name to this specification in the presence of two subscribing witnesses.
